UNITED STATES PATENT OFFICE

2,214,910

START-STOP REPEATER SYSTEM

Louis M. Potts, Evanston, Ill., assignor to Teletype Corporation, Chicago, Ill., a corporation of Delaware

Application December 16, 1937, Serial No. 180,066

12 Claims. (Cl. 178—70)

This invention pertains to regenerative telegraph signal repeaters and more particularly to telegraph repeating devices of start-stop regenerative type in which reproduction of signals is effected by a photo-electronic system.

In systems for comparatively slow speeds of transmission in which transmission is effected by comparatively long electrical impulses, an ordinary electromagnetic relay having mechanically controlled electrical contact points may repeat the impulses successfully, since the long electrical impulses have ample time to bring the connecting transmission conductor to full electrically charged condition and thereby have time to deliver to the electromagnetic relay an electrical impulse sufficient for its operation, whereupon the relay operates to renew the current strength of the individual signal impulses, and any distortion in comparative lengths of successive signal impulses will be negligible because it constitutes but a small portion of the total length of each signal impulse.

With increase of speed in signaling, the individual electrical impulses become shorter, and the invariable components of distortion introduced by the electrical constants of the connective conductor and the mechanical constants of the repeating relay become a greater proportion of a total signal impulse until a point is reached where distortion of the individual signal impulses limits the speed of signaling, and to effect still higher signaling speeds, it becomes necessary to provide repeating devices which will not only renew the strength of the original signal impulse but will also restore the original relations of impulse lengths. In consideration of mechanically distorted signals, the feature of chatter in the contacts of a repeating relay is a form of mechanically produced distortion and operates to shorten the effective value of repeated impulses unduly.

Accordingly, an object of this invention is to provide a regenerative repeater in which original electrical conditions of controlling signals are faithfully repeated in a controlled circuit in original time values as well as in renewed strength, and in which the beginning and ending of the respective signals are effected with a minimum of transit time.

A still further object of the invention is the provision of a photo-electric regenerative repeating device of simple construction and operation.

A feature of the invention is to provide a regenerative repeater in which starting mechanism

is placed under mechanical control of a device responsive to received line signals, while the repeater is in its stop or idle condition, and in which each of the signal impulses is repeated by a photo-electronic device, which starts and stops each retransmitted electrical signal impulse with great suddenness despite any mechanical sluggishness of the mechanical parts which receive, store, and control the received signal impulse.

The above objects and features are attained by utilizing mechanical principles of start-stop selectors in combination with electronic retransmitting members so arranged that the retransmitting members are controlled through a mechanical start-stop element to determine the timing of retransmitted signal impulses and the retransmitted impulses are determined in marking or spacing nature by a mechanically moved shutter element which exercises its optimum photo cell control by a mid-portion of its movement where its mechanical speed is relatively rapid. The shutter element further does not propagate in any repeated electrical impulse any electrical distortion resulting from any mechanical vibration or chatter resulting upon starting or stopping the mechanical shutter.

A system including this invention comprises a controlling circuit having an electromagnet, a controlled circuit having photo-electronic control means, and a mechanical device controlled by the electromagnet and controlling the admission of light to the photo-electronic means. While structure is disclosed for repeating in but one direction in the system shown, the apparatus is such that it is available as a structural unit for circuit systems operating to effect transmission in both directions upon a single line.

The apparatus of the invention comprises start-stop cams associated through a friction clutch with a driving motor and with means for holding the cams normally stopped, but subject to control of a starting signal in a controlling line circuit. In response to a starting signal impulse, the cams are started and continue in motion for a complete cycle of revolution, which is also a complete code cycle of operation, and then the cams come to rest in readiness for the next code cycle.

Controlled by the cams is a shutter member for controlling the admission of light into a photo-electronic retransmitting member, the shutter member being such that it is controlled by the cams for timing the instant of the beginning and ending of every retransmitted signal impulse, but is permitted by the cams to take a

transmitting position for each signal impulse in accordance only with the electrical nature of the instantly received signal impulse so that the beginning of each retransmitted impulse has its electrical nature controlled by the instant received impulse but has its beginning and duration controlled by the cams. A maximum abruptness in admitting and excluding light to and from the photo-electric means is attained by mechanical construction of the shutter. The start impulse and the stop impulse, which respectively precede and follow the impulses of the intelligence code signal, also are repeated in regenerative manner.

16 A more complete understanding of the invention may be had from the following description taken in connection with the accompanying drawing wherein,

Fig. 1 shows a sectional view of mechanical elements of a structure illustrating this invention, taken on line 1—1 of Fig. 2;

Fig. 2 shows a sectional view of the mechanical elements taken on line 2—2 of Fig. 1;

Fig. 3 shows a section taken at 3—3 of Fig. 1 through the photo-electronic cabinet including a showing of an optical system and of a retransmitting circuit;

Fig. 4 shows an enlarged section of the shutter, and

Fig. 5 illustrates a simplified illuminating system.

Referring to Fig. 1, line wire 1 connects transmitting substation 2 and repeating signal receiving magnet 3 in a controlling circuit with grounded battery 4. Repeating means is positioned between magnet 3 and amplifier 10, whence line wire 5 completes the circuit to receiving substation 6. Magnet 3 has an armature 11 pivoted to a supporting frame by pivot 12 with retractile spring 13 and an arm 14 which constitutes a follower for a six-toothed cam 15 fixed to cam sleeve 16, which is sleeved upon a continuously rotating power shaft 17. Shutter member 20, is pivoted about pivot rod 12 and has a free end carrying a thin flat shutter 19 with slots 18 and is urged angularly by compression spring 21 extending between member 20 and armature 11, and alternatively by compression spring 22 extending between member 20 and a lug 23 formed integrally upon arm 14. The member 20 is further positively controlled in position by engagement between a thin edge of member 20 and a similar thin edge of a lock lever 25, which is pivoted to the frame at 26, is tensioned by spring 27 and which constitutes a follower for a seven-toothed cam 30 which is fixed with cam 15 upon cam sleeve 16. Retransmitting shutter member 19 has slots 18 which open or close slots 28 in cabinet 24 according to the position assumed by shutter member 20 and shutter 19.

Referring to Fig. 2, power shaft 17 carries a fixed collar 32 and a spring pressed feather washer 33 between which are friction discs 34 and 35 which hold frictionally a cam sleeve assembly comprising the sleeve 16, start arm 37, the six-toothed cam 15, the seven-toothed cam 30, and a clamping nut 40. Start arm 37 engages gate 41 pivoted at 42 upon adjustable member 43, which is locked in position by clamp nut 44. Gate 41 is restrained by latch 46 pivoted at 47 upon the member 43 and tensioned by compression spring 48 extending from latch 46 to member 43. Extending between latch 46 and armature 11 of magnet 3 is a linkage comprising a start member 50 pivoted to the frame at 51 and engaging

a plunger 52 sliding in frame part 53 and engaging at its upper end a projection 54 on armature 11.

Cabinet 24 is constructed to be light tight with the exception of a plurality of slots 28, and contains a photo-electronic cell 8 so positioned as to be controlled by light reaching the interior of the cabinet through slots 28. In front of the cabinet is a thin shutter 19 carried upon member 20 and provided with a plurality of slots 18 which are related to slots 28 in such manner that in one position of shutter 19 all slots 28 will be obscured, while in the alternative position of shutter 19, a slot 18 will be positioned in alignment with each slot 28. The width of each slot 28 exceeds the width of each slot 18 so that a limited travel of shutter 19 is permitted before any slot 18 registers with its companion slot 28, and a similar amount of travel is permitted to the shutter 19 after the initial registration has been effected. This overtravel has the effect of permitting shutter 19 to attain a mechanical speed before the slots 18 cut off the light by passing the edges of the slots 28. This introduces into the retransmitted signal a delay but no distortion, since the mechanical delay in cutting off the light can be adjusted to be equal to the mechanical delay in turning on the light. The shutter thus moves through three operating zones in each half-cycle of operation. Referring to Fig. 4 and taking center line 80 of slot 18 in shutter 19 as a moving line of reference, shutter 19, while moving the center line 80 downward through light zone 81 from position 82 to position 84, does not vary the illumination of photocell 8. While moving the center line 80 from position 84, where lower edge of slot 18 aligns with lower edge of slot 28, through zone 83 to position 86, where upper edge of slot 18 aligns with lower edge of slot 28, the shutter 19 changes the photo-cell 8 from lighted condition to darkened condition. The shutter moves the center line onward through dark zone 85 and engages a mechanical stop at position 88, after which any bounce or vibration which does not exceed the double width zone from 86 to 89 will not vary the dark condition of photo-cell 8.

The effect of shutter 19 upon photocell 8 is increased by providing a plurality of slots 18, producing a plurality of beams. The quantity of light supplied to photocell 8 is represented by a product of the width of slots 18 multiplied by the effective length of the slots. When a desired quantity of light has been determined, this quantity may be admitted to cabinet 24 by dimensioning properly the length and width of slots 18. Providing a plurality of slots resulting in a plurality of beams increases the effective length of the slots and reduces the required width thus the reducing movement required of the shutter 19. Since a minimum movement of shutter 19 facilitates its operation, the provision of multiple slots is desirable.

An optical system is disclosed in Fig. 3 comprising an illuminant 55, a pair of condensers 56 and 57, and a collimator 58, which produces a beam 59 ample to cover all of the slots 18 and 28 when the slots are in alignment and which serves thus to control the photo-cell 8 at such times.

Amplifier 10, Figs. 1 and 3, comprises valves 7 and 9, potentiometer resistor 60, and a system of three circuits; namely, a potentiometer input circuit for grid control of valve 9, a plate circuit for valve 9 which is at the same time a 75

local potentiometer circuit for grid control of valve 7, and an output plate circuit connected to line 5 and substation 6.

The potentiometer input circuit comprises a portion of potentiometer resistance 60 as a source of current, contactor 61, conductor 66, photo-cell 8, conductor 62, resistor 63, and contactor 64, with a potentiometer branch conductor 65 extending to grid of valve 9. Preferably, the resistance value of resistor 63 is so chosen that a maximum change in potential of conductor 65 results in response to a change in illumination of photo-cell 8. Adjustments of contactors 61, 64, and 71 are such that current flows in the plate circuit of valve 9 when photo-cell 8 is dark, but does not flow when photocell 8 is illuminated. To produce this effect, the grid of valve 9 is at all times negative with reference to cathode 67, being but slightly negative, due to proximity of contactors 64 and 71, when photocell 8 is dark, and increasing in negative value when photocell 8 decreases in resistance by virtue of illumination.

The local potentiometer circuit mentioned for grid control of valve 7 comprises a portion of potentiometer resistance 60 as a source of current, contactor 71, cathode 67 and anode of valve 9, conductor 72, resistor 73, and contactor 74. When, by virtue of illumination of photo-cell 8 and resultant control of grid 68, there is no current in the plate circuit of valve 9, the potential of the grid 77 of valve 7 is of positive polarity with reference to the cathode 78 of valve 7 and a plate current flows in line conductor 5 of a value determined by position of contactor 74, constituting a marking signal current in substation 6. When, by virtue of a dark condition existing upon photo cell 8, current flows as described above in the local potentiometer circuit including valve 9 and resistor 73, a potential condition is established upon potential branch conductor 75 and therefore upon grid 77, such that the plate current of valve 7 is suppressed.

In review, a signal of marking nature in a system including the invention exemplified in the drawing includes a marking signal current in the transmitting substation 2 and line conductor 1, an energized condition of magnet 3, the shutter 19 in the position shown, slots 18 and 28 in alignment as shown in Fig. 3, an illuminated condition of photo-cell 8, estoppel of current in plate circuit of valve 9, and a plate current in valve 7 constituting a marking signal current in line 5 and substation 6.

For a signal of spacing nature, with shutter 19 closed and with photo-cell 8 dark, transmission is effected as follows: Resistance of photo-cell 8 is at its higher value and potential from resistor 60 through contactor 64 and resistor 63 effects a potential upon grid of valve 9 to render the valve conducting and the grid of valve 7 is rendered negative, rendering the plate circuit of valve 7 non-conducting and estopping current from line conductor 5, producing at substation 6 a signal of spacing nature.

In Fig. 5 an alternative illuminating system is illustrated, in which a concentrated illuminant 80 is positioned near the shutter 19 and the optical system is omitted.

The operation of the mechanical system is as follows: An interruption of current at transmitter 16 at substation 2 of the controlling line 1 will cause deenergization of signal receiving magnet 3, which will release armature 11 permitting cam follower 14 to drop into the path of

the six-toothed cam 15 and permitting the armature extension 54 to shift the plunger 52, which will operate lever 50 to cause operation, in turn, of latch 46, which will release gate 41 to release start arm 37, and thus to permit the rotation of cam sleeve 16 and its cams 15 and 30 by the power of shaft 17 through friction of discs 34 and 35. Operation of armature 11, when released by deenergized magnet 3, also compresses spring 21 and relaxes spring 22, but transmitting shutter member 20 resists the spring pressure because it is locked by lever 25, which is in the path of the seven-toothed cam 30, which cam now is starting. The first mechanical action of the cam sleeve 16 and its cams is to operate the lock lever 15 by cam 30 thereby releasing shutter member 20 which moves shutter 19 and repeats the signal from transmitting station 2 to the receiving station 6 by controlling the photo-cell 8, which in turn controls valves 9 and 7, which produces a spacing signal in line conductor 5, as described above. The operation of lock lever 25 is momentary because of the small arcuate dimension of the lobes of the toothed cam 30, and member 20 immediately is relocked. In operating to unlock 25 the shutter member 20, locking member 25 permits release of the member suddenly at the instant when the end of lever 25 leaves the end of member 20. The impulse from station 2 now being repeated to station 6, thus has been determined in point of time solely by the movement of the cam 30 acting through lever 25 to release member 20, but its electrical nature whether a marking current in line 5, because valve 7 is conducting, or whether a spacing current in line 5, 35 because valve 7 is non-conducting, is determined solely by the position of the armature 11 which has been controlled solely by the signal received in magnet 3 under control of station 2.

At this time, lever 25 again projects into the path of teeth of cam 30, arm 14 projects into the path of cam 15, and the next action is the engagement of a tooth of cam 15 with its follower arm 14 whereby armature 11 is moved toward or against its controlling magnet 3. This 45 action occurs six times in a cycle, each such occurrence at about the middle of six of the code impulses; namely, first, second, third, fourth, and fifth impulses and the stop impulse of the code. In each instance, armature 11 will be held by 50 magnetism of energized magnet 3 if the instant signal be a closed circuit at station 2, but in each instance armature 11 will be released by the passing of tooth of cam 15 from follower arm 14 and armature 11 will be withdrawn from de- 55 energized magnet 3 by spring 13 if the instant signal at transmitting station 2 be such that the transmitting station 2 is open circuit to deenergize magnet 3. In each such instance, action of follower 14 by cam 15 and retention or release 60 of armature 11 by magnet 3 will be followed by operation of lock lever 25 by cam 30, which will permit shutter member 20 to operate the shutter to open or close the light cabinet 24 accordingly as magnet 3 has retained armature 11 or has 65 released armature 11, urging shutter member 20 downward or upward when released by lever 25.

Thus there is provided a regenerative repeating mechanism having a small number of mechanical parts and no electrical contacts, whose 70 parts are controlled by electro-mechanical means and the motion of whose parts control the illumination or darkening of the photo-electric cell 8 in code manner in response to received signals.

The application of the photo-electronic retrans- 75

mission has been made here with reference to a specific type of mechanical control device for operating the shutter member 20 and shutter 19. It will be understood that many modified forms 5 of shutter and shutter controlling member may be designed to cooperate with variant forms of mechanical controlling devices.

What is claimed is:

1. In a regenerative repeater, signal receiving 10 means, a photo-shutter having a closed and open position, means to determine the succession of open and closed positions of the shutter according to the operation of the signal receiving means, a rotary start-stop timing member started into 15 rotation by said signal receiving means responsive to an initial signal of a group of signals, and means responsive to said timing member to determine the actual time of the change from open position of said shutter to close position of 20 said shutter or vice versa, controlled by said timing means.
2. In a signal receiving system, means to transmit code signals, timing means started by said signals at the beginning of each code signal and 25 operating independently for the remainder of the signal, a photo-shutter having an open and closed position, means controlled by the signal to determine the position of the shutter for each element of the signal, means to determine the time 30 of change from open to closed and vice versa controlled by the timing means, means to produce a beam of radiant energy, means to modulate the beam by said shutter, a photo-electric cell activated by said beam, and means to transmit electric telegraph signals according to the 35 activation of the photo-electric cell.
3. In a regenerative repeater, signal receiving means, means to produce and extinguish a beam of light under the control of the receiving means, 40 means normally at rest and started into rotation by said signal receiving means in response to a starting signal to time the intervals between producing and extinguishing the beam, a photo-electric device activated by said beam, and means 45 to transmit electrical signals controlled according to the operation of the photo-electric device.
4. In a telegraphic repeating device, an armature controlled by received electrical signals, a photo-electronic member having a shutter elastically 50 articulated to said armature, and cam-controlled mechanism initially responsive to said armature and operating to render said shutter operable by said armature at a predetermined instant.
5. In a telegraphic repeating device, an armature controlled by received electrical signals, a photo-electronic member having a shutter, elastic means connecting said shutter and said armature, and cam-controlled mechanism initially 55 responsive to said armature and operating to render said shutter operable by said armature through said elastic means.

6. In a telegraphic repeating device, a signal receiving magnet, an armature for said magnet, a photo-electronic retransmitting member having a shutter, a tension member connecting said armature and said shutter to operate said shutter in response to movement of said armature, and a locking member engaging said shutter to restrain said shutter whereby an instantly received signal is stored in said tension member. 5

7. In a telegraphic repeating device, an armature controlled by successive received signals, a photo-electronic member having a control member elastically articulated to said armature, and cam-controlled mechanism rendering said control member responsive to said armature at successive instants of beginning of a plurality of electrical retransmission time intervals. 10 15

8. In a telegraphic repeating device, an armature controlled by successive received signals, a photo-electronic retransmitting member having a movable shutter, means selectively controlled by said armature and acting to urge said shutter to move, a locking member engaging and restraining said shutter, and means operating said locking member to release said shutter repeatedly. 20 25

9. In a telegraphic repeating device, an armature responsive to successive received signal impulses, a photo-electronic retransmitting member having a controlling shutter elastically connected to said armature to follow movements of said armature, and cam controlled mechanism engaging said shutter and restraining said shutter after said armature has been shifted and until a mechanically predetermined instant. 30 35

10. In a telegraphic repeating device, a receiving member responsive to received electrical signals, a photo-electronic retransmitting member controlled by said receiving member, a rotary member responsive to said receiving member to begin rotation, and means associating said rotary member and said retransmitting member to control said retransmitting member repeatedly during each rotation to begin retransmission of successive received signals. 35 40

11. In a telegraphic repeating device, a photo-electronic retransmitter, a timing member therefor, a restraining member engaging and restraining said timing member, an armature controlled by received signals, and means operated by said armature and acting to control said timing member and said photo-electronic retransmitter. 45 50

12. In a telegraph transmitting device, a photo-cell, a shutter controlling the illumination thereof, and means to operate said shutter through a preliminary zone of motion prior to varying the illumination of said cell, through an intermediate zone of motion while varying the illumination of said cell, and through a final zone of motion after varying the illumination of said cell. 55 60
